Patented Feb. 27, 1917.

INVENTOR:

William Warren Plimpton

Chas. H. Luther

ATTORNEY:

UNITED STATES PATENT OFFICE.

WILLIAM WARREN PLIMPTON, OF PROVIDENCE, RHODE ISLAND.

DESIGN FOR A GAME-BOARD.

50,403.

Specification for Design.

Patented Feb. 27, 1917.

Application filed April 29, 1916. Serial No. 94,505. Term of patent 7 years.

To all whom it may concern:

Be it known that I, WILLIAM WARREN PLIMPTON, a citizen of the United States, residing at Providence, in the county of Providence and State of Rhode Island, have invented a new, original, and ornamental Design for a Game-Board, of which the following is a specification, reference being had to the accompanying drawing, forming part thereof.

The figure in the drawing is a face view of a game-board showing my new design.

I claim:

The ornamental design for a game-board as shown.
